SPEED GOVERNOR FOR ELECTRIC MOTORS

Walter A. Anderson, Bridgeport, Conn., assignor
to Underwood Elliott Fisher Company, New
York, N. Y., a corporation of Delaware

Application June 29, 1938, Serial No. 216,464

1 Claim. (Cl. 200—80)

This invention relates to electric contact speed governors such as are used on accounting machines and the like, and more particularly to a speed regulating adjustment therefor.

5 Adjustment devices of this character generally employ a set screw threaded in the flexible contact feather and arranged to be adjusted toward and from the actuating arm of a centrifugal governor. Such a device is disclosed in United States 10 Patent No. 1,984,512, issued to Walter A. Anderson on December 18, 1934. An unsatisfactory feature of this method of adjustment is that it is impractical to make the adjustment while the machine is running, necessitating therefore, several 15 adjustments by trial and error method until a satisfactory operating speed is obtained. Another disadvantage of this type of adjusting device is that the governor housing must be removed in order to gain access to the set screw.

20 An object of the present invention, therefore, is to provide an adjusting means for an electric contact governor which is readily accessible and permits the desired speed regulation while the machine is running.

25 With this and incidental objects in view, the invention consists in certain novel features of construction and combinations of parts, the essential elements of which are set forth in the appended claim, and a preferred embodiment of 30 which is hereinafter described with reference to the drawing which accompanies and forms part of the specification.

In the drawing:

Figure 1 is a perspective view of an electric contact governor embodying the invention,

Figure 2 is a right side elevation of the governor with the housing shown in section, and

Figure 3 is a sectional view taken on the line 3—3 of Figure 2.

10 The armature shaft 1 (Figures 1 and 2) has secured on its end a bracket 2 of rigid construction. A flexible actuating feather 3 is secured at one end to bracket 2 by screws 4 and carries a weight 5 at its other end, the center of mass 15 of the weight being normally to the left (Figure 2) of the plane of rotation of the pivot point of feather 3, the pivot point being designated by the numeral 6. Feather 3 is of two-part construction, as shown, one of the parts having a 20 round boss 7 located at the axis of rotation of the armature shaft and feather. A rigid contact support 8 fixed on two sleeves 11 (Figure 3) is supported for sliding movement on two studs 12, and is held out of electrical contact with the 25 studs by insulating material as shown. The sup-

port 8 carries a bearing 13 (Figures 1 and 2) in which is slidably supported a plunger 14 of hard insulating material. A cross bar 15 is mounted in insulated condition on studs 12 and is secured in spaced relation to support 8 for sliding movement therewith by screws 16 passing through insulating bushings and collars 17 and threaded in the support. A contact feather 18 is fixed on bar 15 for sliding movement on studs 12, and is likewise held out of electrical contact with the studs by insulating material as shown. A thumb screw 21 journaled in a stationary bar 22 spanning and insulated from the ends of studs 12 is threaded in cross bar 15 (Figures 1 and 3) to adjust support 8, plunger 14 and feather 18 as 15 a unit, bodily toward or away from actuating feather 3. Nuts 23 threaded on the ends of studs 12 hold the parts in assembled position as shown. A knob 24, preferably of insulating material, is fixed on screw 21, and extends through an aperture 20 in the governor housing (Figure 2) so as to be readily accessible. Feather 18 carries a set screw 25 in axial alignment with plunger 14, and carries a contact 27 to cooperate with a similar oppositely disposed contact 26 secured in support 25. Wires 28 and 29 carry current through support 8, contacts 26 and 27, and feather 18, and from there to the electric motor (not shown) so that the motor is supplied with current only while contacts 26 and 27 are closed. When current is 30 started through wires 28 and 29 and through the motor, armature shaft 1 starts rotating, whereupon weight 5 moves to the right about pivot 6 (Figure 2). Its amount of movement to the right increases with the speed of rotation of 35 armature shaft 1. As weight 5 and feather 3 move to the right, boss 7 slides plunger 14 to the right, contacting the left end of set screw 25. Further acceleration of armature shaft 1 results in additional movement of the plunger 14 to the 40 right, causing feather 18 and contact 27 to be moved to the right away from contact 26. This breaks the circuit to the motor, causing it to decelerate until weight 5 and the associated parts return a short distance to the left, at which 45 time contact 27 again touches contact 26, re-establishing the circuit. When these parts find their equilibrium, contacts 26 and 27 are made and broken in such rapid succession that the motor runs at a speed that is sufficiently constant 50 for practical purposes.

When it is desired to increase or decrease the speed of the machine, it is merely necessary to turn knob 24 clockwise or counter-clockwise respectively (Figure 1) to bring the contact unit 55

26—27 and plunger 14 farther from or nearer to the actuating feather 3. Adjustment of the speed in this manner can be made while the machine is running because the turning of thumb screw 5 21 has no influence on the tension of one contact against the other. Rotation of knob 24 clockwise causes screw 21 to increase the distance between feather 3 and plunger 14, causing contacts 26—27 to break later and thereby increase the speed of the machine. Conversely, rotation of knob 24 counter-clockwise decreases the distance between feather 3 and plunger 14, causing contacts 26—27 to break sooner and thereby reduce the speed of the machine. The thread of screw 21 is much 10 finer than that shown in the illustration in Figure 3, this thread being enlarged in the showing for clearness of illustration, making possible a very fine adjustment of the speed.

While the form of mechanism herein shown 20 and described is admirably adapted to fulfill the objects primarily stated, it is to be understood that it is not intended to confine the invention to the one form of embodiment herein disclosed, for it is susceptible of embodiment in various

forms all coming within the scope of the claim which follows.

What is claimed is:

In a speed governor for an electric motor, a 5 rotatable shaft, a bracket secured to one end thereof, an actuating feather having one end secured to the bracket and the opposite end provided with a weight and being free to move in a direction substantially parallel with the axis of the shaft in response to changes in the speed of 10 rotation of the shaft, a stationary support, a rigid contact feather and a flexible contact feather, a carriage slidable on the stationary support and having secured thereto one end of each of the contact feathers, a plunger slidably supported in the rigid contact feather at the axis of rotation of the shaft, one end of the plunger lying adjacent a portion of the flexible contact feather and another portion of the plunger lying adjacent 15 a portion of the actuating feather, and a micrometer adjusting means for moving the contact feathers and plunger bodily toward or away from the actuating feather.

WALTER A. ANDERSON.
